UNITED STATES PATENT OFFICE

EDGAR H. BRISTOL, OF FOXBORO, MASSACHUSETTS, ASSIGNOR TO THE FOXBORO COMPANY, OF FOXBORO, MASSACHUSETTS, A CORPORATION OF MASSACHUSETTS

RECORDING INSTRUMENT

Application filed June 6, 1925. Serial No. 35,352.

This invention relates to recording instruments such, for example, as recording pressure gages and recording thermometers and more particularly to mechanisms having 5 directly to do with the usual changeable paper chart or record disc used on such instruments and aims to make the use of the instruments more convenient and the records more accurate.

10 My invention will best be understood by reference to the following description of the recording instrument shown by way of example in the accompanying drawings in which structures illustrative of my invention 15 are embodied. In these drawings:

Fig. 1 is a front elevation of a recording instrument, the usual glazed door being omitted;

20 Fig. 2 is a side elevation as seen from the right of Fig. 1 with the parts in another position of adjustment;

Fig. 3 is a central vertical section with parts broken away, the position of the parts being as in Fig. 2;

25 Fig. 4 is an enlarged central section of the chart-holding hub; and

Fig. 5 is a section of the line 5—5 of Fig. 4.

Referring to the drawings, I have there 30 shown a recording instrument of well known form embodying a casing 7, the front of which is closed by a dial plate 9 and which houses a suitable clock movement and a suitable measuring instrumentality such, for instance, as a helical Bourdon tube or a set of 35 diaphragms. The measuring instrumentality operates the pen 11 which swings over the dial plate 9 and is adapted to record the conditions measured on the paper chart 13 which 40 is secured as by means of the chart hub 15 to the time shaft of the clock movement to rest against and rotate over the dial plate 9. The instrument would ordinarily be provided with a suitable glazed door, not shown, 45 carried by the hinge knuckles 17.

Referring to Fig. 4, the hub 15 by which the chart is secured to the time shaft 19 may consist of an inner part secured to that shaft and an outer removable cap. The former 50 preferably comprises a cylindrical barrel

portion 21 adapted to pass through the central opening of the chart, which latter may be placed over this barrel portion freely by a simple movement of axial approach and at the inner end of this barrel portion there is provided a shoulder 23 against which the chart may be clamped to rotate with the time shaft. This clamping may be effected by the removable cap which preferably includes a sleeve 25 adapted to surround the barrel portion 21, the sleeve having an annular shoulder 27 opposing shoulder 23, the chart being clamped between these two shoulders with sufficient pressure to cause the rotation of the same with the time shaft.

To secure the removable cap embodying the sleeve 25 upon the inner member of the hub the latter may be hollowed out to receive a stem 29 on the cap, a suitable spring catch being provided for engaging the stem within the hollow of the inner element, this catch being preferably arranged to exert a longitudinal tension on the removable cap to effect a clamping pressure between the opposed shoulders 23 and 27. In the present embodiment of the invention the catch is formed by a ball 31 housed in a suitable recess in the inner element so that it projects into the hollow therein, which ball is normally pressed inwardly by a suitable spring, 80 conveniently in the form of a flat spring 33 in extent somewhat greater than a semi-circle, which clasps around the inner element of the hub, preferably being housed in an annular groove 35 therein. The end of the spring 33 bears upon the ball 31 and may be provided with a hole 37 receiving the convex surface of the ball to aid in positioning the parts. The ball may engage in a suitable recess 39 in the stem 29 85 of the removable cap, this recess preferably being an annular groove as shown to permit engagement of the parts irrespective of the relative angular position thereof and for other purposes which will appear hereafter. The end of the stem 29 may, as shown in Fig. 4, be provided with a coned inner end 90 cooperating with the convex surface of the ball to provide a mutual camming action facilitating the interengagement of the 100

parts. The rounded surface of the ball entering the groove 23 likewise tends to draw the cap toward the left in Fig. 4, pressing shoulder 27 against shoulder 23 and may grip the chart with sufficient tightness to insure proper driving of the same from the time shaft. In the preferred embodiment of the invention herein shown the single ball 31 provides a laterally acting catch tending to press stem 29 laterally (downwardly in Fig. 4) into frictional engagement with the wall of the recess in the inner hub element. By this frictional engagement driving of the cap by the inner element carried by the time shaft 19 is assured. To ensure rotation of the chart suitable means are provided whereby the cap grips the same and I have herein shown teeth 41 formed on shoulder 27 of the sleeve 25, the teeth being adapted to pierce the chart when the cap is applied.

The chart as used on these instruments is ruled with suitable lines usually designated with the hours of the day or other time periods. Obviously if a chart is placed on the instrument at nine o'clock in the morning, it should be so positioned that the pen will coincide with the nine o'clock line on the chart. In the present instance provision is made permitting angular adjustment of the chart after it has been secured in position on the time shaft. For this purpose the cap or outer member of the chart hub is arranged for rotative movement relatively to the time shaft without relaxation of the hold on the chart and means are provided whereby the chart may be rotated with this outer member or cap independently of movement of the time shaft. As has already been noted, the cap may be manually rotated relative to the inner element of the hub on the time shaft because the ball 31 engages in annular groove 39 in the stem 29 of the cap. Rotative adjustment of the cap to control the angular position of the chart is provided for by the teeth 41 formed on the shoulder 27 which pierce the chart. An annular groove 43 in the shoulder 23 of the inner member receives the teeth 41 and permits rotative movement of the sleeve. Thus, if the sleeve is rotated as by means of the enlarged head 45, the chart will likewise be rotated by the teeth 41 which grip the same yet it will be held in the position of adjustment to which it is brought by this rotation and will be rotated by the time shaft at normal speed as soon as the adjusting movement is stopped since the cap which grips the chart by means of the teeth 41 is frictionally clutched to the shaft with sufficient firmness to effect driving without slippage.

As seen in Fig. 1, the division lines on the chart indicating periods of time are closer together near the inner circumference of the chart than they are at the outer circumfer-

ence. When the chart is changed the pen 11 may be as shown near the inner circumference of the chart. To facilitate adjustment of the chart to the proper time line, advantage may be taken of the larger scale 70 at the margin of the chart and for this purpose the member 47 may be mounted on the edge of the dial plate 9 and have an indicating point 49 projecting inwardly over the edge of the chart to cooperate with the division lines adjacent the outer margin thereof, this point being located in the line of movement of the pen 11. In the embodiment of the invention shown the member 47 is mounted by means of clamping screws in a 80 circumferential slot 51 of the dial plate 9, this providing for the initial adjustment of the member to its proper position in the line of movement of the pen. To facilitate the introduction of the chart beneath the pointer 85 49, which should lie closely adjacent the same, the member 47 may be provided with a finger 53 curving outwardly from the face of the dial plate, as indicated in Fig. 3, providing in cooperation therewith a guiding 90 passage into which the edge of the chart is readily introduced to be slid to its final position under the pointer 49 which lies relatively closely adjacent the face of the chart.

The removable cap of the chart hub is 95 preferably attached to the instrument to prevent its loss. To facilitate its application and removal and also in the present embodiment of the invention for other purposes the construction best illustrated in Fig. 1 may be 100 adopted. I have there shown the removable cap as swivelled in the end of a wire bail having its legs 55 pivoted in posts 57 projecting from the dial plate beyond the margin of the chart. The sides of the bail adjacent the end may be pressed inwardly as indicated in dotted lines at 59 in Fig. 1 to provide a partially circular portion fitting 110 (see Fig. 2) in an annular groove 61 on the cap. The parts may be assembled by passing the cap between the legs of the bail until the groove lies substantially in the plane of the latter and then pressing it toward the end of the bail to snap past the shoulders provided by the bending thereof at the 115 points 59. It will be well understood that the pivotal mounting of the cap by means of the bail 55 permits it either to be applied to the time shaft in the position shown in Fig. 1 or snapped free therefrom and swung to 120 one side to the position shown in Fig. 2 out of the way of the chart 13.

The construction of the chart hub herein before described is made by the subject of a divisional application, Serial No. 444,972, filed April 17, 1930.

The chart 13 during operation of the instrument should lie flat and smooth against the dial plate, particularly in the region which lies at any given time beneath 130

the recording pen. For this purpose suitable means may be provided for holding down the edges of the chart, that is, for holding them closely confined to the face of the dial plate without, however, hampering the rotation of the chart. In the illustrative embodiment of the invention I have shown a preferred form of holding means having advantages in itself and also cooperating in a manner which will appear as the description proceeds with other devices embodied in the instrument illustrated. The holding means shown may include a relatively fixed device adjacent the upper edge of the instrument, here shown as comprising a wire 63 mounted in a post 65 projecting from the edge of the dial plate 9 and bent downwardly closely to overlie the margin of the chart. In the illustrated embodiment of the invention the wire 63 is then bent somewhat upwardly again (Fig. 3) and extended inwardly toward the center of the chart to provide a bearing support utilized in the installation of other mechanism presently to be described. The outward bending of this extension also provides for guiding the edge of the chart in under the portion of the wire which serves to hold the margin of the chart adjacent the dial plate. The chart may further be held adjacent the lower circumference thereof by means of a bowed wire 67 pivoted near its ends to the posts 69 projecting from the dial plate, the main portion of the bowed wire being adapted to encircle a substantial arc of the chart adjacent its margin. Because of its pivotal mounting, this bowed member may either lie closely adjacent the dial plate in the position shown in Fig. 1 to confine the chart or may be raised to the position of Figs. 2 and 3 to provide a clearance between the same and the dial plate through which the chart may be easily introduced and slid beneath the holding means at 63 and engaged on the barrel 21 of the chart hub (see Fig. 3) or through which the chart may be withdrawn.

In the embodiment of the invention shown the bowed member 67 is normally spring-pressed toward the raised position of Figs. 2 and 3 and this may be effected by providing the bowed member 67 with a cross piece 71 extending chord-like thereacross, which cross piece may be soldered to the bowed member 67 adjacent its ends and may have projecting ends providing trunnions pivoting the bowed member to the posts 69. Between its ends the member 71 may be bent to provide a double crank with crank arms 73 and a suitable torsion spring 75 may be interposed between one of the crank arms (that shown at the right in Fig. 1) and the bearing provided by the extension inwardly of the member 63.

It will be understood that suitable means

are provided for holding the member 67 in its lowered position against the force of the spring 75 and in the preferred form of the invention shown the operation of this hold-down member is effected automatically and consequentially upon the movement of the removable cap of the chart hub so that when this cap is removed the holding member will be raised by the spring freeing the chart for removal and when the cap is applied in position the holding member will be lowered to hold the edge of the chart against the dial plate while the chart is secured to the time shaft by means of the cap. In the form of the invention shown the bail-like handle 55 is utilized to effect this action and it will be clear from Fig. 1 that in the construction shown the lower arm 55 of this bail will bear against the member 67 at a point remote from the pivotal center thereof and may be utilized to press downwardly the member 67 against the force of the spring when the cap is swung inwardly for application to its chart-holding position at which time the arm 55 is brought into a position generally paralleling the face of the chart. Conversely when the cap is removed and swung to the position of Fig. 2, the arm will be removed from over the bowed member 67, releasing the same to the action of the spring which will raise it to the position of Fig. 2.

I have herein shown the double throw crank provided on the member 71 as located so that the wrist of the crank underlies the pen 11, the crank thus serving as a pen lifter, as clearly appears from Figs. 2 and 3. When the spring 75 is permitted to act, the end of the pen will be lifted away from the chart and dial plate and the old chart may be removed and the new one placed in position without any danger of marks being made thereon by the pen. In the construction shown and just described obviously the pen lifter is operated automatically consequentially upon the application or removal of the cap, it being lifted from the chart when the cap is removed for the purpose of changing the chart and lowered into cooperation with the new chart when the cap is again applied to clamp the latter.

To facilitate the removal of the chart when released at its margin suitable means may be provided for lifting at least a portion of the chart from the dial plate 9 so that the fingers may reach beneath the margin of the chart to grasp the same with the thumb and fingers for removal. For this purpose I may provide a lever 77 which in the present instance is loosely engaged over and suspended by one of the posts 69 and normally hangs under gravity flatly against the dial plate 9. The lever 77 may have an arm 79 extending inwardly under the margin of the chart and it will be under-

stood that if the lever is rocked in the manner shown in Fig. 2 to raise this arm, the edge of the chart underlain by this arm will be raised as shown in that figure and the fingers may readily be introduced under the margin of the chart to grasp the same.

While the movement of the lever might be effected in any desired manner, it may be correlated with the other mechanisms just

10 described and made consequent in its action on the removal and application of the cap. Herein the upper end of the lever 81 is bent somewhat outwardly above the post 69 to provide a crank arm which is presented in 15 the path of the extended end 83 of the bowed member 67 so that as the latter swings upwardly to the position of Fig. 2 when the cap is removed from the chart hub, the end 83 moving inwardly will rock lever 77, raising arm 79 thereof and causing it to lift the chart. When the cap is replaced and the bowed member 67 again lowered, the lever 20 77 will return to its position against the face of the dial plate 9 by gravity.

25 I shall briefly recapitulate the operation of the mechanisms just described in the embodiment of the invention illustrated. Suppose that the parts are in the position of Fig. 1 and that it is desired to change the

30 chart. The removable cap is seized and pulled away from the time shaft and swung over to the right in that figure to or toward the position it occupies in Fig. 2. The lower arm 55 is thus moved away from the bail 35 67, the spring 75 acts on the crank arm 73 and swings the bowed member 67 about the axial line connecting the posts 69, the member 67 moving to the position shown in Fig. 2. As it does this, the wrist of the crank 73

40 lifts the pen 11 away from the dial plate, as shown in Figs. 2 and 3. Also the extended end 83 of the bowed member acts on the end 81 of lever 77 moving the latter to the position illustrated in Fig. 2 and raising the edge 45 of the chart. The fingers may then grasp the lower edge of the chart, which preferably, as shown in Fig. 3, still remains engaged over the barrel 21 of the chart hub and by an outward movement it is disengaged from that barrel and then drawn

50 downwardly and removed from the instrument. A new chart may then be inserted. It is slid upwardly through the wide space between the dial plate 9 and the raised member 67 and beneath the raised pen and its upper edge is slid under the holder 63 adjacent the upper edge of the dial plate. The central opening of the chart is roughly hooked or placed over the barrel 21 of the

55 chart hub in the manner shown in Fig. 3 and it is then sustained in this position and may be released by the fingers. The cap of the chart hub is next swung downwardly and the parts engaged. When this is done

60 the bowed member 67 is pressed down again

against the action of the spring 75 to hold the lower margin of the chart close to the dial plate. The rocking of the crank permits the pen to be lowered into position to mark on the chart and the lever 77 is released so that the chart may lie flat against the dial plate.

70 When the removable cap is thus applied, the sleeve 25 will press the chart home over the barrel 21 and against the shoulder 23 75 toward which it is pressed by the shoulder 27. When the parts are thus engaged the fingers holding the cap by means of the head 45 may be turned to rotate the cap independently of any movement of the inner 80 member and of the time shaft and the teeth 41 engaging the chart will move the same relatively to the barrel 21 and the chart may be brought into proper position of angular adjustment after it has been applied to and 85 secured to the time shaft. The pointer 49 facilitates getting this adjustment accurately and quickly.

90 It will be understood that in referring to the chart as resting against the dial plate and as being held down at the margins I do not mean that it is clamped against the plate but merely that it is supported closely adjacent thereto and is maintained flat and smooth but free for easy rotation over the 95 face of the dial plate.

96 I have described in considerable detail the particular embodiment of my invention shown by way of example in the accompanying drawings. It is obvious that the structure shown is highly organized. In par-

100 ticular provision is made for releasing the chart, for raising the pen and for lifting the margin of the chart and all these operations are coordinated one with another and are made consequential upon the application and removal of the cap of the chart hub. Obviously various of these mechanisms might be utilized in other combinations or certain of the functions dispensed with, 105 some or all of them might be independently operated or operated by other means, whether in one or both phases, and devices of different structure might be utilized to effect one or more of the functions described. 110

115 The construction shown and described in detail is therefore to be understood as a preferred and highly refined embodiment of more generic principles and what I claim as 120 new and desire to secure by Letters Patent I shall express in the following claims.

Claims:

1. A recording instrument comprising a dial plate, a time shaft for supporting a 125 chart to rest against and rotate over said plate and means for holding the margins of the chart including a bowed member secured at its ends to the plate and having a main portion encircling a marginal portion 130

of the chart and beneath which the chart may be slid for attachment to said shaft.

5 2. A recording instrument comprising a dial plate, a time shaft for supporting a chart to rest against and rotate over said plate and means for holding the margins of the chart including a bowed member pivoted at its ends to the plate and having a main portion encircling a marginal portion of the 10 chart and swingable alternatively to hold the chart close to the plate or to provide a clearance facilitating the application of the chart.

15 3. A recording instrument comprising a dial plate, a time shaft for supporting a chart to rest against and rotate over said plate and means for holding the margins of the chart including a bowed member pivoted at its ends to the plate and having a main 20 portion encircling a marginal portion of the chart, a spring normally acting to swing said portion away from the chart, a removable cap for securing the chart to the time shaft and a carrier for the cap arranged to 25 move the member against the spring when the cap is applied.

4. In a recording instrument in combination with a dial plate, means for holding a chart thereagainst for rotation thereover comprising an element on the dial plate extending over the edge of the chart at one side thereof, a bowed member pivoted near its ends on the plate and having a main portion encircling the margin of the chart 35 on the opposite side and pivotally movable alternatively to a position holding said margin to the plate and to a position providing a clearance through which the chart may be inserted or withdrawn from beneath said 40 element.

45 5. In a recording instrument in combination with a dial plate, means for holding a chart thereagainst for rotation thereover comprising an element on the dial plate extending over the edge of the chart at one side thereof and extended to provide a bearing for a spring, a bowed member pivoted near its ends on the plate and having a main portion encircling the margin of the chart 50 on the opposite side, a crank carried by said member, a spring interposed between said bearing and crank and means for holding said member in position against the force of said spring.

55 6. A recording instrument comprising a dial plate, a time shaft projecting therethrough, means for attaching a chart to the time shaft to rest against and rotate over the dial plate, said means comprising a 60 removable cap, hold-down means on the dial plate adapted to extend over the margin of the chart and movable toward and from the same, and means for holding said hold-down means in operative position actuated 65 by the movement of applying said cap.

7. A recording instrument comprising a dial plate, a time shaft projecting therethrough, means for attaching a chart to the time shaft to rest against and rotate over the dial plate, said means comprising a 70 removable cap, hold-down means on the dial plate adapted to extend over the margin of the chart and movable toward and from the same, and means for automatically lifting said hold-down means away from the chart 75 rendered effective when said cap is removed.

8. A recording instrument comprising a dial plate, a time shaft, means for attaching a chart to the shaft to rest against and rotate over the dial plate comprising a barrel 80 on the shaft over which the chart may freely be placed, means for clamping the positioned chart to rotate with the shaft and means on the dial plate opposing the margins of the chart to hold them close to said plate, said 85 means being movable at least in part to provide a clearance between the same and the dial plate through which the chart may be slid and placed over said barrel.

9. A recording instrument comprising a 90 dial plate, a time shaft, means for attaching a chart to the shaft to rest against and rotate over the dial plate comprising a barrel 95 on the shaft over which the chart may freely be placed and a removable cap for clamping the positioned chart to rotate with the shaft and means on the dial plate opposing the margins of the chart to hold them close to the plate, said means being operatively associated with said cap to move at least in part 100 when said cap is removed to provide a clearance between the same and the dial plate through which the chart may be slid and placed over said barrel.

10. A recording instrument comprising a 105 time shaft and means for securing a chart thereto having a removable cap, means for holding down the edge of the chart having a permanent mounting on said instrument permitting movement of said means itself 110 and means for moving said holding means to and from operative position respectively when the cap is applied and removed.

11. A recording instrument comprising a 115 time shaft and means for securing a chart thereto having a removable cap, an arm pivoted to the instrument carrying said cap and a device operated by said arm moving into opposition to the margin of the chart when said cap is applied.

12. A recording instrument comprising a 120 time shaft and means for securing a chart thereto having a removable cap, a device fixedly and movably carried on the instrument opposing the margin of the chart and 125 normally spring-pressed away from the same and means operated by the movement of applying said cap for forcing said device toward the chart.

13. A recording instrument comprising a 130

dial plate, a time shaft, means for attaching a chart to the shaft to rest against and rotate over the dial plate comprising a barrel on the shaft over which the chart may freely be placed and a removable cap for clamping the positioned chart to rotate with the shaft and means permanently mounted on the dial plate opposing the margins of the chart to hold them close to said plate, said means being movable at least in part to provide a clearance between the same and the dial plate through which the chart may be slid and placed over said barrel and being operatively associated with said cap to be held in operative position against the chart margin when the cap is applied.

14. A recording instrument comprising a dial plate, a time shaft, means for attaching a chart to the shaft to rest upon and rotate over the dial plate and a lever underlying a marginal portion of the chart and movable to lift the same for grasp by the fingers to facilitate removal of the chart.

15. A recording instrument comprising a dial plate, a time shaft, means for attaching a chart to the shaft to rest upon and rotate over the dial plate comprising a barrel over which the chart may be freely placed and means for clamping the chart to rotate with the shaft and a lever underlying a marginal portion of the chart movable to lift the edge of the same from the dial plate for grasping with the fingers to facilitate removal of the chart from said barrel.

16. A recording instrument comprising a dial plate, a time shaft, means for attaching a chart to the shaft to rest upon and rotate over the dial plate, said means comprising a support for the chart and a removable cap and a piece underlying a marginal portion of the chart to raise the same for grasp by the fingers, said piece operatively connected to said cap for movement to raise the chart when the cap is removed.

17. A recording instrument comprising a dial plate, a time shaft, means for attaching a chart to the shaft to rest upon and rotate over the dial plate, said means comprising a support for the chart and a removable cap and a piece underlying a marginal portion of the chart to raise the same for grasp by the fingers, said piece operatively connected to said cap for movement to raise the chart when the cap is removed, said connections providing for return of the piece to inoperative position when the cap is replaced.

18. A recording instrument comprising a dial plate, a time shaft, means for attaching a chart to the shaft to rest upon and rotate over the dial plate, said means comprising a support for the chart and a removable cap, a piece underlying the chart to move at least a part of the same away from said dial plate, said piece being operatively connected to

said cap for movement to move the chart when the cap is removed.

19. A recording instrument comprising a dial plate, a time shaft having a barrel over which a chart may be placed to rest against and revolve over said dial plate, means opposing the margin of the chart to hold it close to the dial plate, said means being movable toward and from the plate and a device having an arm underlying a marginal portion of the chart for lifting the same from the plate for grasp by the fingers to facilitate removal of the chart from the barrel and a portion in the path of said holding means to be operated thereby.

20. A recording instrument comprising a dial plate, a time shaft having a barrel over which a chart may be placed to rest against and revolve over said dial plate, means opposing the margin of the chart to hold it against the dial plate, said means being normally spring pressed away from the plate, a cap for securing the chart to the barrel to rotate with the chart having a mounting constructed to move said holding means toward the chart against the spring pressure when the cap is applied and a device having an arm underlying a marginal portion of the chart for lifting the same from the plate for grasp by the fingers to facilitate removal of the chart from the barrel and a portion in the path of said holding means to be operated thereby.

21. A recording instrument comprising a dial plate, a time shaft for supporting a chart to rest against and rotate over said plate, means for holding the margins of the chart including a bowed member pivoted near its ends to the dial plate and having a main portion encircling a marginal portion of the chart, a lever having an arm underlying the chart and an arm in the path of an end of said member whereby the first arm is raised to lift the chart when the member is swung to release the chart and means for controlling movement of said parts.

22. A recording instrument comprising a dial plate, a time shaft for supporting a chart to rest against and rotate over said plate, means for holding the margins of the chart including a bowed member pivoted near its ends to the dial plate and having a main portion encircling a marginal portion of the chart, a lever having an arm underlying the chart and an arm in the path of an end of said member whereby the first arm is raised to lift the chart when the member is swung to release the chart, a removable cap for securing the chart to the shaft and a mounting for said cap for controlling said member and lever through the application and removal of said cap.

23. A recording instrument comprising a dial plate, a time shaft, means for attaching a chart to said shaft to rest upon and

- rotate over the dial plate, holding means on the dial plate for overlying a marginal portion of the chart to hold it close to the dial plate, said means being movable away from the chart and a piece underlying the chart 5 for raising said marginal portion to permit grasp of the same by the fingers, said holding means and said piece being interconnected for conjoint operation.
24. A recording instrument comprising a dial plate, a time shaft, means for attaching a chart to said shaft to rest upon and rotate over the dial plate, means movable toward and from the margin of the chart for holding it close to the dial plate, a piece underlying the chart and operatively correlated with said means to be lifted when said means are moved away from the chart whereby to raise the chart.
25. A recording instrument comprising a dial plate, a time shaft, means for attaching a chart to said shaft to rest upon and rotate over the dial plate, comprising a barrel on the shaft over which the chart may be freely placed, means movable toward and from the margin of the chart for holding it close to the dial plate, a piece underlying the marginal portion of the chart which is released for lifting when said means are moved away from the chart thereby to raise a margin of the chart to be grasped by the fingers to facilitate the removal of the chart from the barrel.
26. A recording instrument comprising a dial plate, a time shaft, means for attaching a chart to the shaft to rest upon and rotate over the dial plate, said means comprising a support for the chart and a removable cap, means opposing a marginal portion of the chart for holding it close to the dial plate movable toward and from the same, means underlying a portion of the chart movable to lift the same, both said means being operatively connected with said cap to provide for release of the chart and raising of the same on removal of said cap.
27. A recording instrument comprising a dial plate, a time shaft, means for attaching a chart to the shaft to rest upon and rotate over the dial plate, said means comprising a support for the chart and a removable cap, means opposing a marginal portion of the chart for holding it close to the dial plate movable toward and from the same, means underlying a portion of the chart movable to lift the same, both said means being operatively connected with said cap to provide for return of said underlying means to non-chart-raising position and of said holding means to position against the chart when the cap is applied.
28. A recording instrument comprising a dial plate, a time shaft projecting therethrough, means for attaching a chart to the time shaft to rest upon and rotate over the
- dial plate, said means comprising a removable cap, a pen cooperating with the chart, a device for lifting the pen, hold-down means on the dial plate adapted to extend over the margin of the chart and movable toward and from the same, means carrying the cap operatively associated with said device and hold-down means to provide for lifting the pen and freeing the margins of the chart when said cap is removed and for lowering the pen and holding the margins of the chart when the cap is applied.
29. A recording instrument comprising a dial plate, a time shaft projecting therethrough, means for attaching a chart to the time shaft to rest upon and rotate over the dial plate, said means comprising a removable cap, a pen cooperating with the chart, a device for lifting the pen, hold-down means on the dial plate adapted to extend over the margin of the chart and movable toward and from the same, means carrying the cap effective when the cap is in position to hold the chart to hold said device to permit the pen to cooperate with the chart and to hold said hold-down means in operative position relatively to the chart margin.
30. A recording instrument comprising a dial plate, a time shaft projecting therethrough, means for attaching a chart to the time shaft to rest upon and rotate over the dial plate, said means comprising a removable cap, a pen cooperating with the chart, a device for lifting the pen, hold-down means on the dial plate adapted to extend over the margin of the chart and movable toward and from the same, means carrying the cap effective when the cap is removed to release said hold-down means and to raise the pen.
31. A recording instrument comprising a dial plate, a time shaft, means for attaching a chart to said shaft to rest upon and rotate over said chart comprising a barrel on the shaft over which the chart is placed, a pen cooperating with the chart, means for lifting the pen from the chart, a piece underlying a marginal portion of said chart movable to lift said portion for grasp by the fingers to facilitate removal of the chart from said barrel, said pen lifting means and said piece being connected to provide for their conjoint action in raising movement.
32. A recording instrument comprising a dial plate, a time shaft, means for attaching a chart to said shaft to rest upon and rotate over said chart comprising a barrel on the shaft over which the chart is placed, a pen cooperating with the chart, means for lifting the pen from the chart, a piece underlying a marginal portion of said chart movable to lift said portion for grasp by the fingers to facilitate removal of the chart from said barrel, said pen lifting means and

said piece being connected to provide for said cap and controlling the crank when their conjoint action both in raising movement and in return to inoperative position.

33. A recording instrument comprising a time shaft and means for securing the chart thereto having a removable cap, a pen co-operating with the chart, means opposing the margin of the chart, means for lifting the pen from the chart and connections for operating said means on removal and application of the cap.

34. A recording instrument comprising a dial plate, a time shaft projecting therethrough, means for attaching a chart to the time shaft to rest upon and rotate over the dial plate, said means comprising a removable cap, a pen co-operating with the chart, a device for lifting the pen, hold-down means on the dial plate adapted to extend over the margin of the chart and movable toward and from the same, said means connected to operate in unison, whereby the margin of the chart is freed and the pen is raised together and the chart held and the pen lowered together.

35. In a recording instrument in combination with a dial plate, a pen movable thereover, means for holding a chart against said plate comprising an element on the plate extending over the edge of the chart at one side thereof, a bowed member pivoted near its ends to the plate and having a main portion encircling the margin of the chart on the opposite side and pivotally movable alternatively to a position holding said margin to the plate and to a position providing a clearance through which the chart may be inserted or withdrawn from beneath said element and a bar extending chord-like across said member and beneath the pen and providing a crank to raise the pen when the bowed member is raised from the chart.

36. In a recording instrument in combination with a dial plate, a pen movable thereover, means for holding a chart against said plate comprising an element on the plate extending over the edge of the chart at one side thereof and extended to provide a bearing for a spring, a bowed member pivoted near its ends to the plate and having a main portion encircling the margin of the chart on the opposite side, a bar extending chord-like across said member and bent to provide a double throw crank, the wrist of the crank underlying the pen, a spring between said bearing and a crank arm and means for holding said member against the force of said spring.

37. A recording instrument comprising a time shaft and means for securing a chart thereto having a removable cap, a pen co-operating with the chart, a crank underlying the pen, a spring tending to rotate the crank in one direction and an arm to rotate the crank against the spring, said arm carrying

70 said cap and controlling the crank when the cap is removed or applied.

38. A recording instrument comprising a time shaft and means for securing a chart thereto having a removable cap, a bail pivoted to the instrument and partly encircling the margin of the chart, a pivoted arm carrying the cap and adapted to press the bail toward the chart when the cap is applied.

39. A recording instrument comprising a time shaft and means for securing a chart thereto, a bail pivoted to the instrument and partly encircling the margin of the chart and manipulatable means for holding the bail in positions respectively close to and distant from said chart.

40. A recording instrument comprising a dial plate, a time shaft, means for attaching a chart to the shaft to rotate over the dial plate comprising a removable cap, a member pivoted to the dial plate and having a portion swinging into proximity to a margin of the chart to hold it close to the dial and connected with said cap to move toward and from the chart when the cap is applied and removed respectively.

In testimony whereof, I have signed my name to this specification.

EDGAR H. BRISTOL.
